DESIGN FOR A COAT

Hyman Frost, New York, N. Y.

Application December 26, 1941, Serial No. 104,843

Term of patent 3½ years

To all whom it may concern:

Be it known that I, Hyman Frost, a citizen of the United States, residing in New York city, in the county of New York and State of New York, have invented a new, original, and ornamental Design for a Coat, of which the following is a specification, reference being had to the accompanying drawing, forming part thereof.

Fig. 1 is a front view of a coat showing my new design.

Fig. 2 is a rear view of the coat shown in Fig. 1 on a reduced scale, and

Fig. 3 is an enlarged fragmentary front view of the coat shown in Fig. 1 with the fronts turned back.

I claim:

The ornamental design for a coat, substantially as shown and described.

HYMAN FROST.
